his Attorney

UNITED STATES PATENT OFFICE.

HUGH F. ELLARD, OF MISSOULA, MONTANA.

CABLE-GRIP.

1,217,163.

Specification of Letters Patent. Patented Feb. 27, 1917.

Application filed July 8, 1915. Serial No. 38,831.

To all whom it may concern:

Be it known that I, HUGH F. ELLARD, of Missoula, in the county of Missoula and State of Montana, have invented certain new and useful Improvements in Cable-Grips; and I do hereby declare the following to be a full, clear, and exact description of the invention, such as will enable others skilled in the art to which it appertains to make and use the same.

The object of my invention is to produce a simple and highly efficient cable or rope grip for use in moving loads such as logs, etc., from place to place by a transmission rope or cable.

In the accompanying drawing, Figure 1 is a side elevation the full lines showing the position of the parts when closed, the dotted lines indicating their open position. Fig. 2 is a detail view of one of the gripping jaws. Fig. 3 is a detail of the link. Figs. 4 and 5 show a slight modification of the jaws.

Referring to the drawing, 1 designates the bar constituting the main frame of the device, and adapted to be made fast as at 2 to a load, while the jaws 3 at its other end are for attachment to the moving rope or cable by which the load is to be transported.

One of the essential features of my invention is to provide means for opening and closing the jaws which will insure the maximum gripping action upon the cable, and at the same time permit of varying the grip according to the size of the cable. I also arrange the parts so that when locked they do not project outward unnecessarily, and hence are unlikely to catch in tree branches or other obstructions. I have shown the bar 1 formed near its forward end with a pair 40 of laterally projecting ears or lugs 4, and a gripping jaw 5. The bar has a second pair of ears or lugs 6 shown at about its central portion, and below these the bar is channeled as at 7 to constitute a receptacle for the main 45 operating lever when the device is locked.

The jaw 8 is carried on a lever 9 fulcrumed on the lugs 4 and the main operating lever 10 is fulcrumed on the lugs 6. Levers 9 and 10 are connected by the link 12. This link is 50 of peculiar formation. It comprises a sleeve

13 shown fulcrumed on the lever 9 and internally threaded while a threaded bar 14 is fulcrumed on the short arm of the lever 10 and is received by the sleeve. This bar has spaced apart lateral portions to receive the 55 short arm of the lever 10 and through these lateral portions extends a bolt 15 having a cotter-pin 16. By this means the bar may be removed from the lever and turned to project it inward or outward relatively to the 60 sleeve to enable the jaws to accommodate various sized cables and to vary the tension of the jaws on the cable as the weight of the load may require.

In order to insure the jaws meeting 65 squarely, that is, to avoid any lateral play between them I have shown the meeting face of one of the jaws provided with alignment pins 17 to be received by corresponding recesses 18 in the meeting face of the opposite 70 jaw.

It is sometimes desirable, in order to avoid pinching or biting the cable when the relative position of the load and the rope is variable, to have the jaws disposed at varying 75 angles to the position of the gripping device. To meet this requirement the jaws may be pivotally mounted on their respective bar and lever, as shown in Figs. 4 and 5, where bolts 19 allow the machine proper to swing 80 relatively to the jaws.

I claim as my invention:

1. In a cable grip, a bar having a jaw, a lever carrying a jaw and fulcrumed on said bar, a second lever fulcrumed on said bar, 85 and means for adjustably connecting said levers.

2. In a cable grip, a bar having a jaw, a lever carrying a jaw and fulcrumed on said bar, a second lever fulcrumed on said bar, a 90 link connecting said levers, and means for adjusting said link to regulate the movement of the jaw carrying lever.

3. In a cable grip, a bar having a jaw, a lever carrying a jaw and fulcrumed on said 95 bar, a second lever fulcrumed on said bar, a link connecting said levers, and means for adjusting said link to regulate the movement of the jaw carrying lever, said link comprising a threaded sleeve fulcrumed to one of 100

said levers and a threaded post fulcrumed to the other of said levers and received by said sleeve.

4. In a cable grip, a bar having a jaw at one end and formed with a channel or recess at its other end, a lever fulcrumed on said bar and having a jaw, an operating

lever, and a link connecting said levers, said operating lever being adapted to be received by said channel or recess when the grip is closed.

In testimony whereof, I have signed this specification.

HUGH F. ELLARD.
